CLAIM

The ornamental design for a container, as shown and described.

DESCRIPTION

FIG. 1 is a perspective view of a container in full lines with a spout in the open position and a handle in the carrying position.

FIG. 2 is a right side elevational view thereof.

FIG. 3 is a left side elevational view thereof.

FIG. 4 is a rear elevational view thereof.

FIG. 5 is a front elevational view thereof.

FIG. 6 is a top plan view of the container.

FIG. 7 is a bottom plan view thereof; and,

FIG. 8 is a perspective view of an another embodiment of the container with the spout in the closed position and the handle in a collapsed position.
